UNITED STATES PATENT OFFICE.

FRED A. HARPFER, OF WHEELING, WEST VIRGINIA, ASSIGNOR TO CENTRAL GLASS WORKS, OF WHEELING, WEST VIRGINIA, A CORPORATION OF WEST VIRGINIA.

DESIGN FOR A VANITY TRAY.

Application filed May 31, 1928. Serial No. 26,940. Term of patent 3½ years.

To all whom it may concern:

Be it known that I, FRED A. HARPFER, a citizen of the United States of America, and resident of Wheeling, county of Ohio, and State of West Virginia, have invented a new, original, and ornamental Design for a Vanity Tray, of which the following is a specification, reference being had to the accompanying drawings, in which—

Fig. 1 is a side elevation of a vanity tray, showing my new design;

Fig. 2 is a top plan view of the same;

and—
Figs. 3 and 4 are sections taken, respectively, on lines 3—3 and 4—4, Fig. 2.

I claim—

The ornamental design for a vanity tray, as shown.

FRED A. HARPFER.
